UNITED STATES PATENT OFFICE

DAVID H. EBINGER, OF COLUMBUS, OHIO, ASSIGNOR TO THE D. A. EBINGER SANITARY MANUFACTURING COMPANY, OF COLUMBUS, OHIO, A CORPORATION OF OHIO

LIQUID-COOLING SYSTEM

Application filed November 11, 1927. Serial No. 232,698.

This invention relates to improvements in mechanical cooling systems, and is particularly directed to a novel type of heat exchanger for use in such system by means of 5 which a structurally simple yet efficient arrangement is provided for reducing the temperature of a liquid circulated through the heat exchanger to render the liquid suitably cool for drinking purposes. Specifically the 10 invention is directed to water coolers of the mechanically cooled type and which are used in office buildings, factories or other similar places, although the invention in other aspects possesses much wider application.

15 In carrying out the invention a heat exchanger has been provided, particularly for use in water coolers, which consists of a casing in which is removably and centrally positioned a mechanically operating cooling unit, 20 the walls of the latter being spaced from the walls of the cylinder to provide a liquid circulating chamber, said chamber having the upper portion thereof provided with a liquid inlet pipe and the lower portion with an outlet pipe, these pipes permitting the circulation 25 of a liquid under pressure through said chamber so that the liquid may contact with the chilled surfaces of the cooling unit to quickly and effectively lower the temperature 30 of the liquid to render the same suitable for the purposes for which it is intended.

Another feature of the invention resides in providing the interior of the casing with a liquid distributor which receives the liquid 35 as the latter enters the casing and retards and directs the flow of the liquid to insure the required contact thereof with the cooled or chilled surfaces of the cooling unit.

For a more detailed understanding of the 40 invention reference is to be had to the following description and the accompanying drawing, wherein:

Figure 1 is a vertical sectional view taken through the improved heat exchanger comprising the present invention,

Figure 2 is a transverse vertical sectional view taken on the line 2—2 of Figure 1,

Figure 3 is an end elevation of the heat exchanger.

50 Referring more particularly to the draw-

ings, the numeral 1 designates my improved heat exchanger in its entirety, and the same is formed to include a cylindrical casing 2 having a closed end 3 and an open end or side which is bounded by an annular flange 4. Secured to this flange is a detachable cover plate 5 which is provided with an opening 6; the axis of which is disposed eccentrically with respect to the principal axis of the casing, screws or the like being employed to 55 detachably connect the plate with the flange 4. Secured to the inner surface of the plate 5 is a cooling unit 7, which is disposed longitudinally within the casing 2 with the outer walls thereof spaced from the inner walls 60 of said casing to provide a water circulating chamber 8. In this instance the cooling unit illustrated may be of the "flooded boiler" type into which sulphur dioxide is introduced in liquid form, then gasified by the 65 extraction of heat from the surrounding media and then mechanically compressed and reduced to liquid form for re-circulation through the unit or boiler 7. I, of course, do not limit myself to the use of this particular type of unit since, obviously, I may utilize with equal efficacy the expansion type of cooling coil in the device, or any other system of mechanical refrigeration. The opening 6 of the plate 5 is situated so as to afford convenient access to the valves 9 carried by the outer end of the boiler for controlling the circulation of liquid and gaseous SO₂ to and from the boiler, and to the associated compressing apparatus, not shown.

85 The liquid to be cooled enters the top of the chamber 8 by way of the perforated inlet head 10, which latter has connection with a pipe 11 leading to a source of liquid supply, such as a circulating water or liquid line. The bottom of the chamber 8 is provided with an outlet head 12 which is connected with a pipe 13 which leads to a point of controlled liquid escape such as a drinking fountain (not shown).

90 Within the liquid circulating space of the chamber 8 there is situated a distributor 14, consisting of a trough-like chamber of sheet metal, which is confined between the top walls 95 of the chamber 8 and the complementary walls 100

of the cooling unit 7. Adjacent to the cooling unit, the distributor is formed with a plurality of openings 15, which are so arranged that the liquid issuing from the distributor is directed upon the outer walls or other chilled surfaces of the cooling unit, and in this manner the necessary intimacy of contact between the liquid and the cooling unit is provided to produce efficient heat interchange, and to lower the temperature of the liquid. The distributor serves in a measure to help retard the flow of the liquid, due to the restricted openings 15, so that the passage of the liquid through the apparatus will be sufficiently slow, even though under pressure, to insure the desired heat exchange.

The inner walls of the casing of cylinder 2 are coated to eliminate corrosion or contamination of the liquid, particularly when the latter is used for drinking purposes. The chamber or circulating space 8 is filled with the liquid and is replenished from time to time by way of the inlet head 10, and is discharged through the head 12 in the bottom of the casing, the same being then led to a bubbling fountain or a circulating water line. At the point where the water enters the cylinder the distributor 14 is used so as to secure efficient distribution of the incoming water over all surfaces of the cooling unit, the distributor functioning to insure that the warmer or incoming water will be kept to the top of the casing and the cooled, usable water at the bottom.

What is claimed is:

1. In a cooling device, a casing open at one end, a detachable closure for the open end of said casing, a cooling unit carried by said closure and situated longitudinally within said casing, the longitudinal axis of said cooling unit being situated above the longitudinal axis of said casing, a liquid intake in the top of said casing above said cooling unit, and a liquid outlet at the bottom of said casing below said cooling unit, said intake and outlet being disposed in substantially registering vertical planes.

2. In a cooling device, a casing, a cooling unit positioned within said casing, liquid inlets and outlets entering opposite sides of said casing, and a distributor positioned between said cooling unit and said casing to initially receive the liquid entering by way of said inlet, said distributor serving to spread the liquid over the full area of said cooling unit.

3. In a cooling device, a casing open at one end, a detachable closure for the open end of said casing, a cooling unit carried by said closure and situated within said casing but spaced from the walls thereof to define a liquid receiving space, liquid inlets and outlets carried by said casing and disposed on opposite sides of said cooling unit

and a liquid distributor surrounding said inlet and provided adjacent to said cooling unit with a plurality of perforations, the distributor serving to insure the spreading of the liquid over the chilled surfaces of said cooling unit.

4. In a cooling device, a casing open at one end, a detachable closure for the open end of said casing, a cooling unit carried by said closure and situated longitudinally within said casing but spaced from the walls thereof, the longitudinal axis of said cooling unit being situated above the longitudinal axis of said casing, a liquid inlet connected with the top of said casing above said cooling unit and a liquid outlet at the bottom of said casing and below said cooling unit, said inlet being above the midportion of said cooling unit.

In testimony whereof I affix my signature.

DAVID H. EBINGER.
